CLAIM

I claim the ornamental design for an unmanned aerial vehicle, as shown and described.

DESCRIPTION

FIG. 1 is a perspective view of an unmanned aerial vehicle in accordance with the present design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken line showings of the unmanned aerial vehicle are included for the purpose of illustrating portions of the unmanned aerial vehicle and form no part of the claimed design.
